UNITED STATES PATENT OFFICE

PERCY J. HINDMARSH, OF LINCOLN, NEBRASKA.

FIRE-EXTINGUISHER.

1,309,624.

Specification of Letters Patent. Patented July 15, 1919.

Application filed September 21, 1918. Serial No. 255,074.

To all whom it may concern:

Be it known that I, PERCY J. HINDMARSH, of Lincoln, county of Lancaster, and State of Nebraska, have invented certain new and useful Improvements in Fire-Extinguishers, and do hereby declare that the following is a full, clear, and exact description thereof.

My invention relates to fire extinguishers, and in particular to the hand or portable kind. My object is to provide a construction which will be cheap to make, easy to handle, and yet of high efficiency, and to this end, my invention consists in the fire extinguisher constructed substantially as hereinafter specified and claimed.

In the accompanying drawings the figure is a vertical section through a hand fire-extinguisher constructed to embody what I now consider the best form of my invention.

My invention has to do with extinguishers of the kind using a solution of bicarbonate of soda and sulfuric acid, which are kept separate until the occasion for use arises, when the acid is emptied from its container into the solution for the generation of the fire extinguishing gas that is discharged on the fire. I employ an elongated cylindrical tank or receptacle 10, of a size that may be readily handled, which at one end only, for access to its interior, has a mouth that is closed by a wax-sealed stopper or closure 11, preferably of rubber, after the alkaline solution has been placed therein. In the inner end of the stopper 11 is a cavity 12, within which is secured a stopper or plug 13 for the mouth of the acid bottle or holder 14, the neck of which enters said cavity. The plug 13 is secured in the cavity, as by means of a pin 15 that extends transversely or diametrically through the stopper 11, and through said plug 13, and after the mouth of the acid bottle (filled with acid) has been pressed over and closed by said plug 13, the space in the cavity around the bottle neck and plug 13 is filled with wax 16, so as thereby to seal the acid bottle closure and thus prevent either escape of acid from the bottle, or access of solution to the acid in the bottle.

The acid bottle, at its bottom, is attached by an eye 17, thereon, to the horizontal arm of an L-shaped rod 18, whose vertical arm passes slidably through a hole in the tank stopper 11, and above the latter has a head

or knob 19 which, when the acid bottle mouth is plugged and sealed as I have described, is sufficiently above the stopper 11 that when struck a blow by the hand, the rod will descend and carry with it the acid bottle, breaking the wax seal, and leaving the plug 13 behind in the stopper cavity, and carrying the bottle neck out of the cavity, and thereby, freeing the bottle, the latter, will be free to swing on its now sole support on the rod 18 at its bottom, will invert and pour its acid contents into the soda solution. The location of the bottle neck in the sealing cavity and its engagement with its plug 13, prevents the turning of the bottle on its pivotal connection with the rod 18. Preferably, the rod 18 has a guide eye 20 which passes over the discharge pipe or tube 21 which leads from the interior of the tank 10 to the outside thereof, said tube passing through a hole in the tank stopper 11, and its outer, or nozzle end being closed, as by means of a screw cap 22.

The discharge tube reaches nearly to the bottom of the tank 10, and within the tank is made flexible, as by means of a section 23 of flexible material, so that its free end may automatically shift about in the tank so as always to be at the lowest point thereof no matter whether the tank is upright, or inclined one way or the other, to give proper direction to the fluid issuing from the nozzle. This always assures that the inlet end of the discharge pipe will reach to the fluid contents of the tank 10, so long as any is present. My apparatus, therefore, is especially fitted for extinguishing automobile fires since the stream can be directed under the car, or in any direction required.

I claim:

1. A fire extinguisher having two chemical containers, one within the other, a stopper for the outer container having a cavity at its inner end within which is secured a closure for the mouth of the inner container, sealing means within such cavity, around the portion of the container therein, means to move the inner container to withdraw its mouth from said closure comprising a rod with which said inner container is pivotally connected, that extends to the exterior of the outer container and a discharge tube reaching from within the outer container to the outside thereof, said

rod having a sliding connection with the portion of the tube within the container.

2. A fire extinguisher having two chemical containers, one within the other, a stopper for the outer container, a closure for the mouth of the inner container, supported from said stopper, a discharge tube reaching from within the outer container to

the outside thereof, an L-shaped rod reaching from said stopper to and connected with the discharge tube, and a pivotal connection between the inner container and said rod.

In testimony that I claim the foregoing I have hereunto set my hand.

PERCY J. HINDMARSH
